UNITED STATES PATENT OFFICE.

JOSEPH WILLIAM SCHLOSS, OF NEW YORK, N. Y.

DESIGN FOR BRAID.

SPECIFICATION forming part of Design No. 33,406, dated October 16, 1900.

Application filed September 20, 1900. Serial No. 30,633. Term of patent 7 years.

To all whom it may concern:

Be it known that I, JOSEPH WILLIAM SCHLOSS, a citizen of the United States, residing at New York, in the county of New York and State of New York, have invented and produced a new and original Design for Braid, of which the following is a specification, reference being had to the accompanying drawings, forming a part thereof.

Figure 1 is a perspective view of a piece of braid, showing my design, the braid being twisted or folded in order that both sides may be seen; and Fig. 2 is a side elevation of the same.

The leading or material feature of my design is a flat braid ornamented with figures located on both sides thereof, the figures on one side being elongated and those on the opposite side being substantially round. More

specifically, the design consists of a flat braid A, ornamented on one side with figures B, somewhat elongated, but narrower than said

braid, and on the other side with substantially round figures C of diameter equal to the width of the aforesaid elongated figures, the figures on both sides being regularly spaced apart. It will also be noted that the figures on one side stand opposite the space between two figures on the other side and that the figures themselves have the appearance of a tuft or pile. Furthermore, the figures stand out clearly against and appreciably above the surface of the braid, which effect will be accentuated when contrasting colors are used.

What I claim is—

The design for a braid substantially as herein shown and described.

In witness whereof I subscribe my signature in presence of two witnesses.

JOSEPH WILLIAM SCHLOSS.
